UNITED STATES PATENT OFFICE.

FRANK LEVI WATSON, OF LYNCHBURG, VIRGINIA.

STEAM-TRAP FOR RADIATORS.

No. 902,126.

Specification of Letters Patent.

Patented Oct. 27, 1908.

Application filed April 18, 1908. Serial No. 427,847.

To all whom it may concern:

Be it known that I, FRANK LEVI WATSON, a citizen of the United States, residing at Lynchburg, in the county of Campbell and State of Virginia, have invented a new and useful Steam-Trap for Radiators, of which the following is a specification.

The invention relates to improvements in steam traps for radiators.

10 The object of the present invention is to improve the construction of steam traps for radiators, and to provide a simple, inexpensive and efficient device, adapted to be readily applied to radiators without necessitating any alteration in the construction of the same or the return pipe, and capable of preventing steam from entering the return pipe and interfering with the operation of the system or causing water hammer.

20 A further object of the invention is to provide a steam trap of this character capable of forming a sufficient water seal for excluding steam from the return pipe, and adapted to permit the escape of air.

25 With these and other objects in view, the invention consists in the construction and novel combination of parts hereinafter fully described, illustrated in the accompanying drawing, and pointed out in the claims hereto appended; it being understood that various changes in the form, proportion, size and minor details of construction, within the scope of the claims, may be resorted to without departing from the spirit or sacrificing any of the advantages of the invention.

In the drawing:—Figure 1 is a vertical sectional view of a steam trap for radiators, constructed in accordance with this invention and shown applied to a portion of a radiator and the return pipe thereof. Fig. 2 is a perspective view of the steam trap detached. Fig. 3 is a perspective view of the cylindrical trap casing. Fig. 4 is an end elevation of the same.

45 Like numerals of reference designate corresponding parts in all the figures of the drawing.

1 designates a bushing of the usual construction, screwed into the threaded opening 2 of a radiator 3 and provided with a reducing opening 4, interiorly threaded for the reception of the threaded end of a return pipe 5. The bushing is provided at its inner face with a chamber 6 in which is fitted 55 an open end 7 of a cylindrical trap casing 8. The outer end of the cylindrical trap casing

is open and is secured within the inner chamber of the bushing in any suitable manner. The trap casing is provided with an inner end wall 9, but it is divided by a transversely disposed segmental partition 10 to form an inner water seal compartment 11. The partition 10, which may be varied in form, is preferably provided with a peripheral flange 12, extending outwardly toward the open end of the casing and suitably secured to the same. The upper edge 13 of the transverse partition is spaced from the top of the casing to provide a passage for the water, and the latter enters the casing through perforations 14 and flows out over the upper edge of the transverse partition. The apertures 14, which form a water inlet, are arranged at the bottom of the chamber in the lower portion of the end wall 9, but the water inlet may be arranged at any other desired portion of the bottom of the inner compartment 11, as will be readily understood. The end wall 9 is provided above the plane of the upper edge 70 of the partition 10 with a small vent aperture 15 for the escape of air. The perforation is not of sufficient size to permit the escape of steam into the return pipe in a sufficient quantity to affect the operation of the system, or to cause water hammer in the pipes. The steam trap is adapted to be applied to radiators with the same facility as the ordinary bushing, and the water contained within the radiator rises in the compartment 11 of the trap casing and forms an efficient water seal and positively cuts off the escape of steam through the water inlet of the casing.

Having thus fully described my invention, what I claim as new and desire to secure by Letters Patent, is:—

1. A steam trap for radiators including a bushing having a reducing opening and provided at its inner face with a chamber, a trap casing having an inner end wall and provided with an open outer end fitted within the chamber of the bushing, and a transverse partition arranged within the trap casing and extending upward from the bottom thereof to form an inner compartment, the upper edge of the partition being spaced from the top of the trap casing and the latter being provided at the lower portion of the compartment with a water inlet.

2. A steam trap for radiators including a bushing having a reducing opening and pro-

vided with a cylindrical chamber, a cylindrical trap casing provided with an inner end wall and having an open outer end fitted within the cylindrical chamber of the bushing, and a substantially segmental transverse partition arranged within the trap casing and extending upward from the bottom to form an inner compartment and spaced from the top of the casing, the latter being provided at the lower portion of the inner end wall with perforations to form a water inlet and having an air vent perforation located above the upper edge of the partition.

3. The combination with a bushing having a reducing opening, of a cylindrical trap casing having an inner end wall and pro-

vided with an open outer end secured to the bushing, and a transverse partition arranged within the trap casing and extending upward from the bottom thereof to form an inner compartment, said trap casing being provided at the lower portion of the compartment with a water inlet and having an air vent at the upper portion of the said compartment.

25

In testimony, that I claim the foregoing as my own, I have hereto affixed my signature in the presence of two witnesses.

FRANK LEVI WATSON.
